[57] CLAIM

The ornamental design for a fitting table, as shown and
described.

DESCRIPTION

FIG. 1 is an illustration, in rear perspective, of the fitting table embodying my new design;

FIG. 2 is an elevational view of one side of the table, the
opposite side thereof being of substantially the same
appearance;

FIG. 3 is a top plan view; and

FIG. 4 is a front elevational view of the table.
